UNITED STATES PATENT OFFICE.

MICHAEL J. FARRELL, OF LEOMINSTER, MASSACHUSETTS, ASSIGNOR TO BLANCHARD ENGLAND COMPANY, OF LEOMINSTER, MASSACHUSETTS, A COPARTNERSHIP CONSISTING OF CHARLES H. BLANCHARD, JOHN F. HYLAND, AND MICHAEL J. FARRELL.

HAIR ORNAMENT.

1,177,693.

Specification of Letters Patent.

Patented Apr. 4, 1916.

Application filed February 9, 1915. Serial No. 7,007.

To all whom it may concern:

Be it known that I, MICHAEL J. FARRELL, a citizen of the United States, residing at Leominster, in the county of Worcester and 5 Commonwealth of Massachusetts, have invented a new and useful Improvement in Hair Ornaments, of which the following is a specification accompanied by drawings, forming a part of the same.

10 The present invention relates to hair ornaments, or barrettes, and has particular reference to an improved construction for articles of this class, which lends itself to cheapness and ease of manufacture, and 15 eliminates waste of material. The manufacture of barrettes in appropriate ornamental designs, from sheet material, such as celluloid or the like, has ordinarily involved the removal, either by means of a jig saw or by a 20 suitable stamping or pressing process, of sections of the material, from the edges and from the inner portions of the sheet, in order to obtain the outline desired, and also to 25 obtain the usual skeleton configuration for the finished article. The labor and time necessary for the production of the articles by these methods is considerable, and the waste of material, incident to the attainment 30 of lightness and skeleton design constitutes a factor to be seriously reckoned with. The present invention contemplates the use of material in rope or strip form, adapted to be bent or otherwise molded into the ornamental shapes desired, and securely 35 retained in such shapes in the manner hereinafter set forth.

Referring to the accompanying drawings, Figure 1 is a side view of a hair ornament constructed in accordance with my invention. Fig. 2 is a bottom, or under side plan view of the same. Fig. 3 is a similar view 40 of another style of ornament embodying my invention.

Like reference characters refer to like 45 parts in the different figures.

In carrying my invention into practice, I attain the desired ornamental shapes and skeleton configuration for the body of the barrette by the use of strip material, of any 50 appropriate cross-sectional shape, as for instance the round shape shown in Figs. 1 and 2 or the rectangular shape shown in Fig. 3. Said body 1 carries on its rear or bottom side, at one end, a hinged tongue

member 2, and at the other end a hook 3 to 55 receive the end of said tongue member 2, when the latter has been inserted through the hair of the wearer.

In the form of invention shown in Figs. 1 and 2 the body 1 is formed from a single 60 strip 4 of material, bent in the form of a figure 8 with the ends 5 of said strip brought into abutting relation to the central portion of the strip on opposite sides of the same. In order to impart rigidity to the 65 structure thus produced, and to prevent displacement of the ends 5 from the positions which they are caused to assume by the bending operation, a member 6 is cemented or otherwise secured to each of the 70 three portions of the continuous strip thus lying in juxtaposition, namely, to the two ends 5 and to the interposed central portion. Said member 6 is disposed upon the 75 front or upper side of the body 1, enhancing the ornamental character of the same, and in addition to its function as a means for retaining the free ends of the strip 4 in proper position, it serves as a shield to cover the square cut ends 5, which, it will 80 be seen, do not need to be made concave, to conform to the contour of the sides of the strip 4 with which they abut, by reason of the use of this member 6, which conceals the unsightliness of the rough unfinished 85 joints. Furthermore, by reason of the provision of said member 6 in the form of a plate or disk, having a relatively extended 90 surface in comparison to the surfaces with which it makes actual contact, the entanglement or catching of the hair in the spaces between the ends 5 and the central portion of the strip 4 is largely guarded against, and the access of such hair to the joints 95 between the member 6 and the three underlying portions of the body 1 is made practically impossible.

The form of the invention illustrated in Fig. 3 involves a body portion 1 of a different shape, the same being constituted by 100 a single strip 7 substantially inclosing a single continuous space, which is contracted at its central portion by bringing the meeting ends 8 of the strip into close relation to the central portion of the strip. A 105 member 9, of sufficient size to bridge the contracted gap thus formed, is secured to the portions of the strip thus lying in juxtapo-

sition, namely, the meeting ends 8 and the oppositely disposed central portion of the strip, serving precisely the same functions as the member 6 in the first described form 5 of invention.

While I have shown and described two forms of my invention, it is to be understood that I contemplate the use of strip material for other shapes and forms than 10 those above described, yet falling within the scope of said invention, which, broadly considered, resides in the use of an overhanging connecting member, such as the plate 6 or the plate 9, disposed in the particular relation above set forth to the free 15 ends of such strip material.

I claim.

1. As a new article of manufacture, a hair ornament having its body portion formed of strip material, a free end of said material being disposed in proximity to an intermediate strip portion with a member secured to and connecting said free end to 20 said intermediate strip portion.
2. As a new article of manufacture, a hair ornament having its body portion formed of strip material, the free ends of said material being disposed adjacent one 25

another with a connecting member, having a relatively extended surface, secured to 30 said adjacently disposed free ends of said material and overhanging the said ends on each side thereof.

3. As a new article of manufacture, a hair ornament having its body portion formed 35 of a single strip of material, with a free end of said strip lying in juxtaposition to an intermediate portion of said strip, and with a connecting member having a relatively extended surface, secured to said adjacently disposed portions of said strip on 40 one side of said strip.

4. As a new article of manufacture, a hair ornament having its body portion formed 45 of a single strip of material, with the free ends of said member lying in juxtaposition on opposite sides of an intermediate section in the length of said strip and with a member secured to said intermediate section and overlying said free ends. 50

Dated this sixth day of February, 1915.

MICHAEL J. FARRELL.
